CLAIM

The ornamental design for a commodity tank for a work vehicle, as shown and described.

DESCRIPTION

FIG. 1 is a top, rear, and left side perspective view of a left commodity tank for a work vehicle in accordance with an embodiment;

FIG. 2 is a left side elevation view of the left commodity tank of FIG. 1;

FIG. 3 is a right side elevation view of the left commodity tank of FIG. 1;

FIG. 4 is a front elevation view of the left commodity tank of FIG. 1;

FIG. 5 is a rear elevation view of the left commodity tank of FIG. 1;

FIG. 6 is a top plan view of the left commodity tank of FIG. 1;

FIG. 7 is a bottom plan view of the left commodity tank of FIG. 1; and,

FIG. 8 is a top, rear, and left side perspective view of the left commodity tank of FIG. 1 showing it in a work vehicle environment.

The broken line representations in the figures show unclaimed environment or boundaries, and thus form no part of the claimed design.

1 Claim, 8 Drawing Sheets
